UNITED STATES PATENT OFFICE

2,580,645

SIDE OPENING SUCTION CLEANER

Ferman C. Doughman, Darien, Conn., assignor to
 Electrolux Corporation, Old Greenwich, Conn.,
 a corporation of Delaware

Application May 24, 1947, Serial No. 750,249

6 Claims. (Cl. 183—37)

1

This invention relates to suction cleaners and is particularly concerned with cleaners having a casing, to receive and house a dust receptacle, which is provided with a side door or cover which may be opened to permit insertion and removal of the dust receptacle.

One of the objects of the present inventive concept is to provide means for inserting and removing the dust receptacle from the suction cleaner without disturbing the position or attachment of a suction hose through which dirt-laden air is led to the cleaner.

A further object of the invention is to provide a structure of the type set forth in which the door is opened in automatic response to variations of the cleaning characteristic of the apparatus.

A still further object of the invention is to provide an arrangement of the type set forth in which the dirt receptacle is moved from the confines of the casing as an incident to the opening of the side closure thereof.

Numerous other objects and features of the present invention will be apparent from the following specification when taken in conjunction with the accompanying drawings, in which:

Fig. 1 is a side elevation partly in section of one embodiment of the present invention;

Fig. 2 is a top plan view of that form of the invention shown in Fig. 1 with the side opened and the dust receptacle presented for disposal, and;

Fig. 3 is a vertical section taken on the lines 3—3 of Fig. 1.

While certain features of the present inventive concept may be embodied in various type of suction cleaners, the invention is more particularly designed for use in connection with the so-called tank type cleaners which are characterized by the provision of a comparatively stationary floor supported casing which houses the motor-fan unit and a dust separating and retaining receptacle. A flexible hose is attached to the casing in such manner that dust-laden air is induced through the hose to be delivered to the dust separating and retaining receptacle.

As distinct from cleaners of this general class now on the market in which the hose is secured to a removable end cover, the present construction provides a rigid and permanently secured end member to which the hose is secured and provides for the removal and replacement of the dust receptacle by provision of a side opening door. The present concept also embodies a movable structure supported by the door to receive

and movably support the receptacle so that upon opening of the door, the receptacle may be displaced from the confines of the casing to be presented for disposal. A further feature of the present construction is the provision of the automatic means whereby the door is opened and the receptacle is presented for disposal in response to variations in the cleaning characteristics of the apparatus. Thus, when the receptacle is fully loaded the door will be opened and the receptacle will be moved for convenient handling without dependence on the vigilance of the user.

Referring more particularly to the drawings, the present embodiment of the invention comprises an elongated and substantially cylindrical casing 10 which is adapted to be supported in spaced relation from the floor by sleighs 11 which permit the casing to be readily moved across the floor in response to the application of force to the cleaning hose 12, the end of which is adapted to be provided with suitable cleaning tools. A lifting handle 13 of conventional form is also provided for the casing 10 so that it may be conveniently carried from place to place. Within the casing 10 there is mounted a vertical perforated bulkhead 14 dividing the casing into a rear motor-fan chamber 15 and a forward dust receptacle chamber 16. Within the chamber 15 there is mounted an electric motor-fan unit indicated at 17 which may be manually controlled by a foot operating control switch 18. The rear end of the casing 10 is closed by an end housing 19 from which air is exhausted through an outlet fixture 20, the fixture 20 preferably including a hose connector 21 to which the hose 12 may be attached when it is desired to use the motor-fan unit as a blower.

The forward end of the casing 10 is closed by a front end structure 22 permanently and rigidly secured to the casing 10, the end 22 being provided with a hose connector 23 to which the hose 12 may be removably secured. Associated with the connector 23 there is provided a fixed air inlet tube 24 which extends through an end plate or bulkhead 25 permanently and fixedly secured within the casing 10 and centrally apertured to receive the tube 24 therethrough. Adjacent the tube 24 end plate 25 is provided with a depression 26 which is adapted to receive a sealing gasket as will be hereinafter described.

One side of the casing 10, preferably the right side looking from the front as in Fig. 3, is cut away from a point extending rearwardly from the plate 25 to a point close to the bulkhead 14, the opening extending vertically from a point

slightly above the forward point of attachment of the sleighs 11 to a point slightly below the top of the side walls, as is shown in Fig. 3. The opening thus formed at the side of the casing 10 is provided with a closure comprising a door 30 hingedly mounted on a vertical pintle 31 mounted within the end member 22 and provided with an encircling spring 32 which normally biases the door 30 to fully opened position as shown in Fig. 2.

Mounted on the door 30 for movement therewith is an apertured front plate 35, the aperture of which is surrounded by gasket 36 adapted, when the door is in closed or sealing position, to be seated within the recess 26 of the plate 25 of the front end. The aperture of the member 35 is fitted with an intake tube 37 which is adapted for registration with an extension through the central aperture 38 of the substantially rigid front end 39 of a dust separating and retaining receptacle, the body of which is indicated at 40. The door 30 also carries with it transversely extending supporting bars 41 here shown as 4 in number which are secured adjacent the lower portion of the door and which in turn carry longitudinally extending guide supports 42, the central one of which is upwardly turned at the front to support a central longitudinally extending guide tube 43. Mounted for sliding movement on the guide supports 42 and guided by the tube 43 is a dust receptacle tray or holder comprising a body 45 and a supporting frame 46. The central lower surface of the frame 46 has an inverted U-shaped channel 47 which overlies the tube 43. The arrangement is such that the frame spaces the body 45 upwardly from the supports 42, while the frame 46 and body 45 move longitudinally upon the supports.

The rear wall of the body 45 of the tray or holder is formed by inwardly turning the side walls and at their juncture there is joined a bracket 48 which supports a forwardly extending guide rod 49 which in turn is slidably mounted within the tube 43 in such manner as to guide the sliding movement of the tray upon the supports 42. The tray is normally urged rearwardly from its retracted position shown in Fig. 1 by the provision of a coil spring 50, the forward end of which abuts a washer 51 fixed to the tube 43 while the opposite end bears against the bracket 48, thus normally urging the tray towards outward movement. For securing the tray against such outward movement when the door is closed there is provided a notch 52 in the rod 49 which when the tray is moved to full inward position as shown in Fig. 1 is engaged by a latch 53 which is pivotally mounted on brackets 54 and is normally urged to the vertical position shown in Fig. 1 by spring 55. As the door opens to the position shown in Fig. 2 the lower extension of the latch 53 strikes an abutment 56 which rocks the latch out of engagement with the rod 49 whereupon the spring 50 will slide the tray rearwardly on the supports 42 as guided by the rod 49 in the tube 43.

The dust receptacle body 40 is preferably formed of inexpensive material, such as paper, its front end being closed by the apertured rigid member 39. For securing the receptacle in proper position within the tray the forward end of the tray is provided with a centrally apertured front end plate 58, the edges of which form channels 59, the arrangement being such that the rigid end 39 of the receptacle may be slid downwardly in the channels 59 which will retain the end 39

in proper position so that the forward sliding movement of the tray will insert the tube 37 through the aperture 38 in order that air will be directed to flow from the hose 12 into the interior of the body 40. When the door is opened, and the holder 45 is moved out to the ejected position shown in Fig. 2, the receptacle may be readily removed by an upward sliding movement and a new receptacle may be readily inserted in a reverse manner.

As hereinbefore stated, the door is spring biased to normally opened position by the spring 32 of the door pintle 31. Such outward movement of the door is, however, precluded during operation of the device by the engagement of a downwardly turned projection 60 of the central longitudinal support 42 with the armature 61 of a solenoid 62. Upon energization of the solenoid 62 the armature 61 is retracted to release the projection 60 and to permit the side door to be opened.

For controlling the energization of the solenoid 62 there is provided a Sylphon bellows 64 and an associated switch 65. The arrangement is such that when the receptacle body 40 becomes clogged with dirt and consequently the suction in the chamber 16 increases, the Sylphon 64 which is in the chamber 16 will expand and close the switch 65 and energize the solenoid 62. If desired, the pressure responsive system may also control the energization of the motor-fan unit either simultaneously with the solenoid 62 or in advance thereof. It is to be understood that the present invention is not restricted to the simplified control system here schematically indicated and reference may be had to the co-pending application of Ferman C. Doughman, Serial No. 676,318, filed June 12, 1946, which describes in detail a pressure responsive system such as may be applicable to the present inventive concept.

In the operation of the present invention it will be understood that with the door opened as shown in Fig. 2 a clean dust receptacle including the body 40 and end structure 39 is positioned within the tray by sliding the end structure into the channels 59. The tray is then pressed inwardly against the tension of the spring 50 whereby the tube 37 is inserted through the aperture 38 of the receptacle. Inward movement of the tray moves rod 49 inwardly and latch 53 engages the notch 52 of the rod 49 to secure the tray in innermost position. Pivotal closing movement of the door thereafter causes the projection 60 to pass the armature 61 of the solenoid 62 which thereafter retains the door against opening movement. After continued use of the cleaner, the receptacle body 40 will become clogged with dust and dirt separated from the inflowing air whereupon the pressure in the chamber 16 outside of the dust receptacle will decrease until such time as the Sylphon 64 will respond sufficiently to close the switch 65. Thereupon the solenoid 62 will be energized to withdraw the armature from the projection 60 and the door will then open under the bias of the spring 32. As the door reaches its maximum open position, the abutment 56 trips the latch 53, rocking it out of engagement with the rod 49, whereupon the spring 50 will move the tray rearwardly to the exposed position of Fig. 2, thus presenting the bag for convenient disposal.

It will be understood that the invention is not limited to the specific structural details herein depicted and that numerous changes and mod-

ifications thereof, may be resorted to without departure from the spirit or scope of the present invention as outlined by the accompanied claims.

What I claim is:

1. In a suction cleaner, a body having fixed wall structure defining a dust bag compartment, said structure being formed with an air inlet opening and with a separate access opening for the insertion and removal of a dust receptacle, a pivotally mounted closure member for sealing said access opening, a dust receptacle holder movably mounted on the inner side of said closure member, means for retaining said closure member in sealing position and said holder in retracted position, and means for opening said closure member and for moving said holder relative to said closure member and outwardly through said access opening.

2. In a suction cleaner, a body having fixed wall structure defining a dust bag compartment, said structure being formed with an air inlet opening and with a separate access opening for the insertion and removal of a dust receptacle, a pivotally mounted closure member for sealing said access opening, spring means biasing said closure member towards open position, means for retaining said closure member in sealing position, a dust receptacle holder slidably mounted on the inner side of said closure member, spring means biasing said holder to move relative to said closure member, means for retaining said holder in retracted position, and means for releasing both of said retaining means.

3. In a suction cleaner, a body having fixed wall structure defining a dust bag compartment, said structure being formed with an air inlet opening and with a separate access opening for the insertion and removal of a dust bag, a pivotally mounted closure member for sealing said access opening, an inlet tube carried by said closure and movable therewith by closing movement thereof into communication with said inlet opening, a dust bag holder movably mounted on the inner side of said closure and movable towards said inlet tube to a retracted position and away from said tube to an ejected position, a dust bag carried by said holder, said bag having an inlet aperture which is brought into communication with said inlet tube when said holder is moved to retracted position, and means for opening said closure member and for moving said holder relative to said closure member and outwardly through said access opening to ejected position.

4. In a vacuum cleaner, a housing formed with an opening, a dust bag within said housing, means

operable for moving said dust bag outwardly through said opening, a closure for said opening, means for producing flow of air through said casing and through said dust bag therein, means responsive to a predetermined pressure drop through said dust bag for opening said closure, and means actuated by opening of said closure for operating the first mentioned means to move said dust bag outwardly.

5. In a vacuum cleaner, a housing formed with an opening, a dust bag within said housing, spring means stressable to produce a force for moving said dust bag outwardly through said opening, means for retaining said spring means in stressed condition, a closure for said opening, means for producing flow of air through said casing and through said dust bag therein, means responsive to a predetermined pressure drop through said dust bag for opening said closure, and means actuated by opening of said closure for releasing the retaining means.

6. In a suction cleaner, a body having fixed wall structure defining a dust bag compartment, said structure being formed with an air inlet opening and with a separate access opening for the insertion and removal of a dust bag, a pivotally mounted closure member for sealing said access opening, a dust bag holder movably mounted on the inner side of said closure member, a dust bag carried by said holder, means for producing flow of air through said casing and through said dust bag therein, means responsive to a predetermined pressure drop through said dust bag for opening said closure member, and means actuated by opening of said closure member for moving said holder relative to said closure member and outwardly through said access opening.

FERMAN C. DOUGHMAN.
